SEAL

Frank Keidel, Elmhurst, N. Y., assignor to The International Seal and Knot Protector Co., New York, N. Y., a corporation of New York

Application June 21, 1934, Serial No. 731,611

4 Claims. (Cl. 292—328)

This invention relates to that type of seal which includes a shackle and a hollow seal body for receiving the ends of the shackle and retaining them therein in locked position.

More specifically the present invention represents an improvement in the type of seal disclosed in my prior Patent No. 1,930,560, issued October 17, 1933. The specific form illustrated in said patent includes a seal body formed from a pair of cup-like members, telescoped and interlocked to provide a casing for a locking plate permitting the passage of shackle ends therethrough in one direction while positively preventing their withdrawal.

The patent illustrates the shackle in the form of a wire which passes through apertures in one end wall of the casing and through apertures in the locking plate, and retained against withdrawal by spring tongues struck out from the plate in such a direction that they permit movement of the shackle through the plate openings in only one direction.

While the construction of the prior patent has proven highly effective in use and practically impossible to open without leaving tell-tale evidence, it might be possible to open it if the wire or shackle has an unusually long bight portion. By patiently pulling on one end leg of the shackle and at the same time twisting it first in one direction and then in the other, the tongues might gradually cut the projections on the shackle leg, or cut a sort of screw thread in the leg and permit the shackle leg to be gradually worked out of the casing.

The main object of this invention is to prevent any such operation, and I accomplish that object by making the shackle of non-circular cross-section, and providing a plate of extremely hard metal having apertures generally corresponding in shape to the cross-section of the shackle legs so that when the legs have passed through these apertures they cannot be twisted even though the bight of the shackle be extremely long.

I accomplish the desired result at a relatively small cost and with substantially no change in the construction of the seal body since the hard metal plate which prevents twisting of the shackle legs may conveniently overlie the locking plate and be retained in position by the same means previously used to secure the locking plate. The manufacturing cost of the present seal with its hard metal anti-twist plate is but negligibly greater than the cost of manufacturing the seal illustrated in my prior patent.

The invention may be more fully understood

from the following description in connection with the accompanying drawing wherein:

Fig. 1 is a perspective view of a seal with the shackle ends locked in position,

Fig. 2 is an enlarged plan view of the casing, 5 the shackle legs being shown in section,

Fig. 3 is a sectional view on the line 3—3 of Fig. 2, and

Fig. 4 is a sectional view on the line 4—4 of Fig. 3.

In the specific form of the invention shown, the seal body includes a pair of cup-like members 10 and 11 telescoped together to form a casing. Secured within the casing is a locking plate 12 having means to engage the ends or legs of a 15 shackle 13 when said ends are inserted through the openings 14 in the end of the cup 10, and locking said legs against withdrawal. The locking plate 12 may conveniently be clamped between the two cup-like members 10 and 11 and spaced a 20 substantial distance from both of the end walls of the casing defined by the cups.

The cups 10 and 11 are preferably stamped or drawn from thin metal and their telescopically interfitting skirt portions are of non-circular 25 shape. In order to clamp the locking plate 12 in spaced relationship with respect to the ends of the casing, the cup 10 is formed with a shoulder 15 upon which the locking plate seats and is clamped by the end of the inner cup 11. 30

In order that the two cup-like members 10 and 11 may be firmly gripped in telescoped frictional engagement, the outside diameter of the skirt of the cup 11 is equal to the inside diameter of the larger end of the skirt of the cup 10. The depth 35 of the cup-like member 11 is such that when the two members are completely telescoped, the bottom of the cup 11 will extend no substantial distance beyond the peripheral edge of the skirt of the cup 10, so that no portion of the member 11 40 may be gripped to pull it out of the member 10. In fact the two members 10 and 11 have a very tight frictional fit and are preferably assembled in a press. The member 11 may taper slightly 45 outwardly toward its open end and the member 10 may be worked in around this taper and actually turned slightly under the bottom of the cup 11 in the assembly press as shown at 10a (Fig. 3).

From the standpoint of the present invention, however, any effective method of interlocking the 50 telescoped cups so that they cannot be separated without leaving tell-tale evidence of tampering, will serve the purpose.

The locking plate 12 is preferably of thin spring 55 steel and has a pair of spaced apertures 16 there-

in registering with the openings 14, through which the legs of the shackle 13 may pass. Thus the legs of the shackle may be inserted through the bottom or end wall of the cup 10 and through the locking plate 12 until they abut the end wall of the cup 11. By pushing the shackle all the way home it is not possible to cut off the wires close to the seal body and reuse the same shackle with the same casing because the remaining stud ends of the shackle will still be held in locking engagement with the plate 12 and the cut-off end of the wire can neither be pulled out nor pushed in.

The shackle or at least the leg portions thereof, are roughened or corrugated or notched or toothed for firm engagement by locking tongues 17 struck outwardly from the plate 14 and permitting the legs of the shackle to pass between them in one direction, but biting into the legs and engaging the teeth or notches to block withdrawal of these legs.

The periphery of the flat locking plate 12 follows the generally oval contour of the hollow seal body, at least to such an extent that any rotary movement of the locking plate within the body is prevented. As an important feature of the present invention, the shackle, or at least the legs thereof, are formed of flat wire stock of rectangular or other non-circular cross-section.

Overlying the face of the locking plate and likewise clamped between the shoulder 15 and the end of the cup, and preferably having a contour corresponding to that of the locking plate 12, is an anti-twist plate 18 of heavier gauge hard metal. This plate has apertures 19 therein registering with the apertures 14 and 16, and through which the legs of the shackle pass.

While I have illustrated the shackle legs as of generally rectangular cross-section, and the openings 19 of similar shape, the important point is to have the shackle legs and the openings of the anti-twist plate of non-circular cross-section, so that the legs of the shackle cannot be rotated, twisted or oscillated in the locking plate.

It is, of course, within the scope of the invention to secure the hard metal plate 18 in position in any suitable location, and by any suitable means, within the casing so long as it serves its intended function of preventing twisting of the shackle legs. The mounting of it between the locking plate and shackle inlet apertures, and the clamping of it by the same means that clamps the locking plate, is preferred because it involves no change in the seal body construction of my prior patent other than forming the skirt of the cup 11 slightly shorter. The locking plate is extremely inexpensive and may be produced by a simple stamping or punching operation.

In the drawing I have shown the seal in its completely assembled position, but seals are usually sold with the flexible shackle separate from the casing. The shackle may be sold as a U-shaped section or as a long coil of wire from which the user may cut off a section of any length and bend it to make the shackle.

The mode of assembly of the shackle body is such that no pressure transmitted by a thrust on the shackle will be operative to effect disengagement of the telescoped cup-like members 10 and 11. In other words, the amount of thrust which can be applied endwise to the legs of the wire shackle without buckling it, is less than the force required to overcome the grip between the two cup members.

Having thus described my invention, what I

claim as new and desire to secure by Letters Patent is:—

1. A seal of the class described, including a pair of telescopically interfitted, generally cup-like members of non-circular shape, cooperatively defining a hollow body, one of said members having a shoulder therein spaced from the ends thereof, and a pair of plates clamped between the shoulder and the end of the other cup-like member, and of a conformation to be retained against rotation within the cup-like members, the end wall of one cup having apertures therein and both of said plates having apertures therein registering with the first-mentioned apertures, a flexible metal shackle including leg portions of non-circular shape adapted to pass through the registering apertures, one of said plates having resilient locking tongues to engage the shackle and block withdrawal thereof, and the other plate being of hard stiff metal and having its apertures closely conforming to the cross-sectional shape of the shackle legs whereby twisting of the legs within the casing is prevented.

2. A seal including a hollow body having apertures in one wall thereof, and a shackle having legs adapted to pass through said apertures and abut the opposite wall, a plate within the body and having resilient portions to prevent the withdrawal of the shackle legs therefrom, and a separate hard substantially inflexible metal plate also within the body to prevent twisting of the shackle legs therein, said shackle being of flexible wire and of non-circular cross-section, and said plate having shackle legs receiving apertures therein of a cross-section corresponding to the cross-section of the legs.

3. A seal including a pair of cup-like members of non-circular shape, each having an end and a peripheral wall of thin metal, the outer diameter of the peripheral wall of one of said members being substantially equal to the inner diameter of the peripheral wall of the other member, said members being telescoped to form a casing, a flexible wire shackle having legs of non-circular cross-section, the end wall of one of said cup-like members having apertures through which the legs of the shackle are adapted to pass, a locking plate having its body portion spaced from both of said end walls, said plate having a pair of apertures in alignment with said first mentioned apertures, and having tongues adapted to engage the legs of the shackle extending therethrough to prevent the withdrawal of said shackle legs, while permitting the entry of said shackle legs, and a hard metal plate disposed against said locking plate and between the latter and said apertured end wall, both of said plates being clamped between said cup-like members, said last mentioned plate having apertures closely conforming to the cross-sectional shape of the shackle legs, whereby twisting of the legs within the casing is prevented.

4. A seal including a pair of cup-like members, each having an end and a peripheral wall of thin metal, said members being telescoped to form a casing, a flexible wire shackle having legs of non-circular cross-section, the end wall of one of said cup-like members having apertures through which the legs of the shackle are adapted to pass, a locking plate having its body portion spaced from both of said end walls, said plate having a pair of apertures in alignment with said first mentioned apertures, and hav-

ing tongues adapted to engage the legs of the shackle extending therethrough to prevent the withdrawal of said shackle legs, while permitting the entry of said shackle legs, and a hard metal plate disposed against said locking plate and between the latter and said apertured end

wall, and having apertures closely conforming to the cross-sectional shape of the shackle legs, whereby twisting of the legs within the casing is prevented, both of said plates being clamped between said cup-like members.
